DEVICE FOR HANGING WASHED CLOTHES

Edward Hughes Roberts, Post Falls, Idaho

Application May 21, 1949, Serial No. 94,713

2 Claims. (Cl. 211—123)

1

My invention relates to improvements in a device for hanging washed clothes.

It is the principal purpose of my invention to provide means that will simplify the work of hanging a washing out to dry. After clothing is washed it is wet and heavy. Most people where they can, wish to hang the clothing out of doors where it may be dried in the sun and in clean fresh air. In the present practice the person hanging the clothes usually carries them from within a wash room and must then do all of the work of hanging them up and distributing them on the clothes line while outside. This is not objectionable when the weather is agreeable but when the weather is cold and windy, the shock of going from the warm wash room to the outside and the handling of the wet clothes while outside is apt to cause the person to contract colds or other illnesses. According to my invention I provide means whereby the washed clothing may be arranged on hangers within the wash room in such a fashion that it may be carried out and quickly attached to a support that is permanently arranged out of doors. The same hangers may likewise be used to hang clothing indoors in a simple fashion.

My invention contemplates the provision of a clothes supporting rack which embodies a relatively long line and a mounting for the line of such nature that several of the racks may be carried side by side on one's arm without difficulty. These racks are so constructed that they cooperate with horizontal bars on a support which is mounted outdoors to permit mounting of the rack by merely shoving it up against the horizontal bar. The individual racks can be released as the clothing dries by a finger tip release that is a part of the rack supporting bar.

The nature and advantages of my invention will appear more fully from the following description and the accompanying drawings illustrating a preferred form of the invention. It should be understood however, that the drawings and description are illustrative only and are not to be considered as limiting the invention except insofar as it is limited by the claims.

In the drawings:

Figure 1 is a vertical sectional view through a supporting post having the clothes rack supporting bars thereon;

Figure 2 is an enlarged fragmentary sectional view taken vertically through a portion of a rack supporting bar;

Figure 3 is a sectional view taken on the line 3—3 of Figure 2;

Figure 4 is a view in side elevation of the clothes support rack;

Figure 5 is a sectional view on the line 5—5 of Figure 2;

Figure 6 is a plan view of the rack supporting post and the inner ends of the rack supporting bars carried thereby;

2

Figure 7 is a sectional view taken on the line 7—7 of Figure 6; and

Figure 8 is a fragmentary perspective view illustrating a wall bracket construction to be used when the clothes are hung indoors.

Referring now to the drawings, the showing in Figure 1 is of a supporting post 10 having a cap member 11 secured thereto in any suitable manner such for example, by means of a bolt 12. The cap member 11 is designed to support a plurality of channel shaped bars 13. These bars preferably are so mounted on the cap 11 that when not used for supporting clothes racks they may be raised to vertical position as indicated in Figure 1. The construction by which this is accomplished is illustrated best in Figures 1, 6 and 7. The cap has up-standing ribs 14 and 15 thereon between which the bars 13 are mounted. Pivot bolts 16 and 17 secure the bars in place. These bolts also secure a spring 18 which is so mounted that it opposes movement of the bars 13 by frictional engagement therewith.

Referring now to Figures 2, 3, 4 and 5, these figures illustrate in detail the construction of the clothes rack 20 and its mounting on the bars 13. As shown best in Figure 4, the clothes rack is a rectangular framework composed in part of a wire or rod 21 and in part of a sheet metal mounting plate 22. The rod 21 has a lower portion 23 which serves to mount the washed items of clothing indicated at 24 by use of the usual clothes pins 25. The portion 23 of the rack preferably is about four feet in length so that it may be conveniently used to support most items which are washed in the home. It can support a multiplicity of small articles such as handkerchiefs, socks and the like, or it can support a single large article such as a sheet. Upright portions 26 and 27 of the rod 21 are bound to the plate 22 by curling the plate over as indicated at 28 and 29 so that it encircles the rod. The top of the plate 22 is curled over as indicated at 30 and 31 to give rigidity to the plate, and, preferably the rod 21 is extended into the curled over parts 30 and 31. It will be noted that the inner ends of the parts 30 and 31 are spaced apart a short distance and are beveled slightly as indicated in Figure 5 at 32 and 33. The plate 22 has a small opening 34 at the center thereof and beneath this opening there is a hand grip 35 formed by bending up a portion of the material from which the plate 22 is constructed.

The rectangular rack just described is sturdy and when not in use occupies very little space. A large group of them may be stacked one upon the other for storage. The overall height of the rack is less than six inches. Light material such as aluminum can be used to reduce its weight.

The channel shaped bars 13 are provided with latch means by which the racks just described can be quickly attached to them. The bars 13 have slots 36 and 37 cut through the webs there-

of. At each side of the slots 36 and 37 I provide cross pins 38 and 39. The pin 38 is closer to the free edge of the channel than the pin 39. The slots 36 and 37 are rounded at their open ends as indicated at 40.

A latch member 41 is pivoted on the pin 39 and has a weight or heavy portion 42 off-set below the pivot pin 39. The portion 42 is adapted to bridge the space between the pins 39 and 38 and to rest upon the pin 38. A finger piece 43 is provided on the member 41 for lifting it.

In order to mount a rack 20 upon the bar 13, the rack 20 is merely shoved upward against the lower side of the rack 13 so that the portion of the plate 22 between the inner ends 32 and 33 passes into a pair of slots 36 and 37. The plate 22 will raise the weighted part 42 of the latch member 41 until the plate 22 is shoved up to the position shown in Figure 5. Then the latch 41 will swing down to latch position in the opening 34 automatically because of the weighted part 42. The rack 20 can then be released and it will remain in place until it is lifted again and the latch 41 is moved out of the opening 34 by raising it to the dotted line position shown in Figure 2 by means of the finger piece 43.

The construction is such that swinging and swaying of the racks 20 on the bars 13 is substantially prevented. Note that when the plate 22 is in position as illustrated in Figure 2, there is very little room for endwise rocking or turning of the racks 20 with respect to the bars 13. It is necessary, of course, to use a plate 22 of adequate thickness to prevent its bending readily at the mid point; however, the parts 30, 31 and 35 cooperate to increase the rigidity throughout its length. The channel bars 13 preferably are constructed so as to leave adequate space above the slots 36 and 37 for the necessary strength of the channel bar against the bending load of the wet clothing. Channel bars 13a, smaller than the bars 13, are used indoors for hanging the racks. In this case I prefer to mount the bars 13a by brackets 44 and pivot pins 45 so that the bars 13a can be swung parallel to the walls 46 on which they are mounted. Of course any suitable bar or rod that will go through the opening 34 can also be used indoors to support the racks 20.

It is believed to be evident from the foregoing description that I have provided a novel means for hanging wet clothing out of doors, which means permits the person handling the clothes to first arrange them indoors on racks and then to quickly fasten the racks out of doors to a support so that the racks cannot swing and entangle the clothing and prevent drying properly.

The person who is hanging the clothing does all of the work with the wet clothes indoors so that her hands can be kept warm. When the clothes are taken out of doors in the cold air her hands may be clad in gloves and they need not contact the wet clothing since she merely pushes the rack up into place and it is immediately latched without her having to manipulate any mechanism of any sort. This device is particularly applicable in the many homes where there is no space indoors for hanging the clothes and they must be hung outside in all kinds of weather.

Having thus described my invention, I claim:

1. Clothes hanging means comprising a rack supporting bar, said bar being channel shaped in cross section with the open side of the channel facing down, said bar having pairs of transverse, downwardly opening aligned guide slots in its side walls, a normally closed latch within the channel

extending across each pair of slots and operable to open under upward pressure thereon and to close when the pressure is released, clothes hanging racks each comprising a plate having a central top portion of a width sufficient to extend across the channel and engages in an aligned pair of the slots in the channel walls, the thickness of the plate portion engaging in said slots being such that snug reception of the plate within said pair of slots is attained and the depth of the plate portion within the slots being several times the thickness thereof whereby to substantially prevent swinging of the plate in a direction lengthwise of the bar, said plate having transversely extending guides positioned at the ends of said central top portion to engage the side walls of said bar and to substantially prevent rocking or horizontal movement of the plate crosswise of the bar, said plate having a latch receiving opening below said central top portion.

2. Clothes hanging means comprising a rack supporting bar, said bar being channel shaped in cross section with the open side of the channel facing down, said bar having pairs of transverse, downwardly opening aligned guide slots in its side walls, a normally closed latch within the channel extending across each pair of slots and operable to open under upward pressure thereon and to close when the pressure is released, clothes hanging racks each comprising a plate having a central top portion of a width sufficient to extend across the channel and engage in an aligned pair of the slots in the channel walls, the thickness of the plate portion engaging in said slots being such that snug reception of the plate within said pair of slots is attained and the depth of the plate portion within the slots being several times the thickness thereof whereby to substantially prevent swinging of the plate in a direction lengthwise of the bar, said plate having transversely extending guides positioned at the ends of said central top portion to engage the side walls of said bar and to substantially prevent rocking or horizontal movement of the plate crosswise of the bar, said plate having a latch receiving opening below said central top portion, said transversely extending guides comprising top edge portions of said plate curled over upon the plate, and said plate having a portion thereof beneath said central top portion bent up to form a hand grip.
